[57] **CLAIM**

The ornamental design for a hands-free kit with a charger function for a cellular phone, as shown.

DESCRIPTION

FIG. 1 is a perspective view from the front, right and top sides of a hands-free kit with a charger function for a cellular phone showing my design;

FIG. 2 is a front view thereof;

FIG. 3 is a rear view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing in FIG. 1-3 represents the middle portion of the electrical cord which is omitted for convenience of illustration.
